UNITED STATES PATENT OFFICE.

THOMAS PETER ROONEY, OF NEW BEDFORD, MASSACHUSETTS.

BOBBIN-HOLDER.

1,265,521.

Specification of Letters Patent. Patented May 7, 1918.

Application filed December 20, 1916. Serial No. 138,027.

To all whom it may concern:

Be it known that I, THOMAS PETER ROONEY, a citizen of the United States, residing at New Bedford, in the county of 5 Bristol and State of Massachusetts, have invented new and useful Improvements in Bobbin-Holders, of which the following is a specification.

This invention relates to improvements in 10 bobbin holders for creel frames, the primary object of the invention being to provide a bobbin holder which admits of the easy motion and the ready application and removal of the bobbin, so that bobbins of different 15 lengths may be employed with ease and facility.

A further object of the invention is to 20 provide a bobbin holder which is simple of construction, inexpensive of production, eliminates the use and handling of skewers 25 and the objections incident thereto, and which is dust-proof, avoids the use of oil as a lubricant and saves wear and tear upon the bobbin, creel frame and the roving.

25 A still further object of the invention is to provide a bobbin holder which will handle fine and coarse rovings with equal facility, which obviates the expense of replenishing parts at frequent intervals, as in 30 the use of wooden skewers, and which reduces labor and maintenance of cost to a material degree.

The invention consists of the features of 35 construction, combination and arrangement of parts hereinafter fully described and claimed, reference being had to the accompanying drawing in which:—

Figure 1 is a sectional elevation showing the application of the invention.

40 Fig. 2 is a detail section on line 2—2 of Fig. 1.

Fig. 3 is a detail section on line 3—3 of Fig. 1.

Referring to the drawing, 1 and 2 respectively designate the upper and lower creel boards or rails of a creel frame, and 45 3 the bobbin having the usual longitudinal passage 4 terminating at its lower end in the opening 5, of greater diameter.

50 The bobbin is rotatably supported from and between the creel rails 1 and 2 by upper and lower holders 6 and 7. The upper holder 6 comprises a head 8 preferably made of porcelain, and which is of semi-oval or 55 elliptical form, having the tapering lower end 9 which fits within the opening 4 at the

upper end of the bobbin and an internal chamber or socket 10. Into this chamber fits the lower end or circular portion 11 of a fastening bolt, 12, the upper end or portion 13 of which is threaded and passes through the creel bar 1 and is equipped at its upper end with a clamping nut 14 and washer 15. The bolt portion 11 forms a 60 spindle on which the head 8 is fitted to 65 slide and revolve, and said portion of the bolt extends into the chamber 10 and through a fiber bushing 15' fitted in said chamber and secured therein by screws 16, the lower end of the bolt being provided 70 with a flange 17, whereby the head is held against downward displacement and its downward motion limited. At the point of junction of its spindle and threaded stem portions the bolt is formed with a shoulder 75 18, and this shoulder is arranged to bear against a base plate or disk 19 which engages the underside of the rail 1 and is clamped by said shoulder in position. This base plate, which may be made of fiber or 80 other suitable material, carries a tubular shield or casing 20 which extends down to 85 embrace the head 8 and serves as a guard to prevent the entrance of dust and dirt. This tube also serves in conjunction with the spindle as a guide for the head 8, which is fitted to slide upward on said spindle so that it may be withdrawn from engagement 90 with the opening 4 in the bobbin, thus permitting different bobbins to be applied and 95 removed with facility and bobbins of different lengths to be used.

The lower bobbin support 7 comprises a head 21 of hemispherical form, having its convex face upwardly disposed and fitted within the opening 5 of the bobbin, whereby the bobbin is supported and held in position upon the creel rail 2. The head 21, which, like the head 8 and base plate 19, is also made of porcelain or other suitable material, is formed with a socket 22 and an annular chamber or cavity. Extending into said socket 22 is the upper circular portion 23 of a fastening and pivot bolt 24, having a threaded stem or shank 25 which passes 100 downward through a threaded opening in a base plate 26 and also through an opening in the lower creel rail 2 and is equipped at its lower end with a nut 27 and washer 28, whereby said bolt and the base plate are fastened in position upon said rail. As shown, 105 the base plate is preferably provided with a 110

thickened or depressed central portion having a threaded opening to receive and engage the bolt, which is provided at the junction of its circular and threaded portions 5 with a shoulder 20' to engage and clamp said base plate in place. Preferably the base plate is formed with an upstanding dust guard or flange 30 which extends into the chamber or cavity of the rotary head 21 and 10 prevents the entrance of dust or dirt, and the outer edge of the base plate is also preferably beveled off, as shown at 31, to shed and prevent the accumulation therearound of any dust, dirt, lint or other foreign substances. 15 Fitted within the socket of the head 21 is a fiber bushing 32 which turns with the head upon the spindle of the bolt, which spindle is provided with a flange 33 to prevent upward displacement of the head 20 and also with a conical point or projection 34 acting as a bearing engaging the crown of the head and on which said head is centered and mounted to rotate. By this construction it will be seen that the lower end 25 of the bobbin will be engaged and held from displacement by the convex surface of the head 21 which will revolve freely on its axis, thus coöperating with the upper head to permit the bobbin to have easy motion without the necessity of employing oil or other lubricant, the construction being such as to obviate the use of skewers and other similar devices and the objections incident thereto. 30 Inasmuch as the heads are made of porcelain or other suitable hard and durable material, it will be evident that the holder will last in active service for a very long period, and as these surfaces are mounted the catching and accumulation of lint and other foreign substances will be prevented and the 35 smooth and even running of the roving without binding, permitted. Furthermore, by simply sliding the head 8 vertically alone or with the bobbin, it will be evident that the bobbin may be unseated from the lower head 40 and removed, and that the construction is such as to facilitate the operation of apply- 45

ing and removing bobbins for various purposes and also adapted to permit of the ready and convenient use of bobbins of different sizes. The construction of the holders, which are adapted for use in connection with bobbins of ordinary type, enables them to be manufactured and sold at a comparatively low cost and to be used with less wear and tear, as well as labor, than holders of ordinary construction and without the manifold objections of such holders. 50 55

I claim:—

1. In a bobbin support for creel frames, 60 the combination with an upper supporting head, of a lower supporting head comprising a base plate, a spindle, a head fitted to revolve upon the spindle and having a cavity therein, and a dust guard flange upon 65 the base plate and projecting upwardly into said cavity.

2. In a bobbin support, an upper supporting head having a tapering curved surface, a lower bobbin supporting member having 70 a hemi-spherical surface, means for mounting the member and permitting the rotation thereof, and a base plate having a flange at the edge thereof coöperating with the edge portion of the hemi-spherical member and 75 preventing the entrance of dust to the mounting means therefor, the base plate and head being spaced apart to form an annular cavity between said elements.

3. In a bobbin support, an upper supporting head having a tapering curved surface, a lower bobbin supporting member having a hemi-spherical surface and carrying a central boss below said surface and having an annular recess surrounding the boss, a pin 85 projecting upwardly through said boss and providing a support upon which said lower bobbin supporting member may rotate, and a base plate having a flange at the edge thereof coöperating with the edge portions 90 of the hemi-spherical member and preventing the entrance of dust.

In testimony whereof I affix my signature.
THOMAS PETER ROONEY.
